F. J. DOWLING

EXPANSIBLE BOLT LOCK

Filed Dec. 29, 1924

UNITED STATES PATENT OFFICE.

FRANCIS J. DOWLING, OF NEW YORK, N. Y., ASSIGNOR TO SEGAL LOCK & HARDWARE CO. INC., OF NEW YORK, N. Y., A CORPORATION OF NEW YORK.

EXPANSIBLE BOLT LOCK.

Application filed December 29, 1924. Serial No. 758,506.

This invention relates to jimmy-proof locks and more particularly to locks of that general nature having an expandible or tilt-able bolt and adapted to be used as rim or 5 mortise locks on swing and sliding doors.

Among the objects of this invention is to provide a lock having an expandible bolt, and novel bearing means for operating said bolt in an efficient and reliable manner to 10 render said lock jimmy-proof.

Another object of this invention is to provide a lock having an expandible or tilt-able bolt to render the lock jimmy-proof, and means having novel bearing and abutment 15 relation therewith to operate the bolt and to retain the same in jimmy-proof position.

Still another object of this invention is to provide a lock having a bolt movable forward into the jamb piece to render the lock 20 jimmy-proof, and a plurality of pivot means for tilting the bolt into expanded position as aforesaid by a combined bearing and sliding movement of the bolt with respect to said means.

25 A still further object of the invention is to provide a lock which can not only be applied with facility to all door or like constructions irrespective of material variations in clearances between the striking edge of 30 the door and the jamb, but particularly one which will continue to be functional and operative even though warping, sagging, or other distortion of these parts relatively may take place after the lock is applied.

35 With the foregoing and other objects in view the invention consists in the arrangement and combination of parts hereinafter described and claimed, and while the invention is not restricted to the exact details of 40 construction disclosed or suggested herein, still for the purpose of illustrating a practical embodiment thereof reference is had to the accompanying drawings in which like reference characters designate the same parts 45 in the several views, and in which—

Figure 1 is an inside view of the lock.

Fig. 2 is a similar view showing the lock in operated position and certain parts in section on the line 2—2 of Fig. 3.

50 Fig. 3 is a section taken on the line 3—3 of Fig. 2.

Fig. 4 is a perspective view of a bolt member.

55 Fig. 5 is a section on the line 5—5 of Fig. 2.

Fig. 6 is a perspective view of a detail of the actuating means.

Referring now more particularly to the drawings, I show the lock as comprising a casing 10 having an opening 11 for the passage of a bolt therethrough to enter the cooperating keeper or jamb piece 12. Within the casing suitable actuating means is provided to operate a novel rocking bolt which provides the essential principle of this invention. Said bolt takes preferably the form of an expandible device constituting a two-part expandible bolt, both members of which are co-operative directly with actuating and controlling means for throwing 65 the bolt outwardly of the lock, and with suitable pivot and abutment means for swinging or expanding the bolt and to retain the same so expanded in jimmy-proof locking engagement with the jamb piece when the 70 bolt has reached the limit of its outward throw.

More specifically, said bolt comprises a plurality of members 13 which are preferably of similar form and arranged in symmetrical relation to each other for similar action and movement. Each bolt member is of substantially rectangular cross section and of longitudinally extended form. The sides of the bolts adjacent to each other are convex, while the outer sides of said members are concave, thus providing in the first instance for the rocking movement of the bolts against or adjacent to each other, and in the latter instance, for the reception and action 80 of suitable pivot means such as the abutment means 14 and the pivotal bearing points 15 at the sides of the opening 11. Thus the inner sides of the bolt members comprise a plurality of faces 16 and 17 making an obtuse angle with each other, while the outer sides of the members comprise a plurality of faces 18 and 19 making a re-entrant obtuse angle with each or equal substantially to the angle aforesaid, the respective faces upon opposite sides of said members being substantially parallel. The bolts 13 are by this construction arranged for movement tilt-able relative to each other and laterally of the general direction of movement of the bolt, the maximum angle of movement being limited by the angle between the faces 16 or 17 depending upon the position of the bolt. The faces 16 and 17 85 intersect in a line which defines the fulcrum 90

100

105

110

about which the bolt members are arranged to rock or to tilt when thrown outwardly of the lock casing into the jamb piece for the purpose of rendering the lock jimmy-proof.

5 Engaging the bolt for operation thereof at the fulcrum aforesaid, is a mechanism comprising an actuating or controlling means 20 having pivotal engagement with the bolt as by means of trunnions 21.

10 More specifically, each bolt member is provided with an open bearing 22 adapted to receive the trunnions at a side of said fulcrum, said trunnions being retained within said bearings by suitable abutment means

15 such as the bearing provided by the co-operating bolt member. The bolt is thus tilttable about the bearing member 20 as for purposes of expansion when the individual bolt members rotate for locking. The member

20 20 is movable for throwing the bolt outwardly into the jamb piece, the bearing being for this purpose movable in a direction substantially parallel to the direction aforesaid. Thus the actuating member 20 is operative by any suitable means such as a crank 23 pivoted thereto at 24, said crank being rotatable about a suitable pin or thimble 25 which is connected to a knob 26 to be rotatable thereby for operating the

25 actuating member. For outward movement of the bearing member to project the bolt, the crank is rotated in the direction of arrow *a*, while to release or withdraw the bolt the direction is that indicated by arrow *b*. To limit the direction of movement of the crank, stop means are provided co-operative with a spring 27 for retaining the bolt in its set or fixed position. The stop means are preferably arranged to be operative be-

30 yond dead center to insure, that the bolt will be properly retained against jimmying. Thus the stop or lug 28 which is preferably of angular section is receivable into a notch 29 formed in the crank member whereby

35 said stop not only brings the movement of the operating mechanism to an end against the tension of the spring 27, but affords additional reenforcement to the crank member in the direction in which a force would be

40 applied to jimmy the lock, thus increasing the strength and reliability thereof. When, however, the bolt is withdrawn into the position shown in Fig. 1, a stop acting between the crank and the actuating member

45 50 comes into play to limit the throw of the crank, said stop means taking the form preferably of a circular extension or lug provided by forming the lip 30 on the crank member upon which the bead 31 for securing the thimble 25 to the crank is formed. The actuating member is provided with a recess 32 to receive the stop means as shown in

55 Fig. 1, a reinforcement rib 33 being provided skirting said recess to insure the

60 65 proper strength in said actuator.

To provide for the proper support of the trunnions 21 and for the movement of the bolt members into abutment relation with each other at the surfaces 16, the bolt members are formed each with a recess 34 to receive the flat shank portion of the actuating member 20. These recesses are formed at the surfaces 16 and are of sufficient depth to provide for the maximum degree of movement of said actuating member. Moreover, said flat shank acts as a guide upon which the bolt members are movable in constant and close relation to each other, thus adding considerably to the stability of the bolt when expanded as shown in Fig. 2.

The means for causing the bolt members to tilt or oscillate while sliding from open to locked position and vice versa includes additional pivot means spaced from the bearing 21. Said pivot means operate by bearing 85 against the bolt members as against the cam surfaces 18 when the bolt is thrust outward or against the cam faces 19 when the bolt is drawn inward, the effect being in each case to cause a tilting or rocking of the bolt members about said bearing. The initial tilting movement is in each case caused by the rounded faces at 15 acting at the junction of the cam faces 18 and 19. When the bolt is drawn inward these points are adapted to return the bolt to position as in Fig. 1. When, however, the bolt is projected outwardly, catch or stop means 35 are operative likewise to finally fix the outward throw of the bolt and to come into abutment against the members 14, whereby any force applied with the intention of jimmying the lock or causing the bolt to collapse into contact at the surfaces 17 is resisted by a stress set up through the bolt members as by the bearing reaction at the surface 16 and along a line joining the abutment members 14. With the actuating member 20 retained by the lock mechanism beyond dead center it is manifestly impossible to cause a movement 110 of the bolt members in any direction to jimmy the lock. If desired additional bearing or cam action can be provided at the sides 36 of the jamb piece. The bolt members are arranged at their outer surfaces for 115 close abutment at 15.

To permit the lock to be operated by a key in the usual manner, a crank 37 is provided having a pin or lug to engage the actuating member as within a notch 38 120 formed preferably in the rib 33 of the member and upon the side thereof opposite to the crank 23 to swing said actuating member as determined by the crank 23 to open or close the lock in the manner described hereinbefore for the operation by means of the knob 26. The crank 37 is for this purpose rotatably mounted upon the cover plate 39 as by means of a thimble 40 to which it is secured and which is slotted to receive the 130

flat shank member 41 whereby it is rotatable as by a key inserted through the key way of the cylinder 42 in a conventional manner. This arrangement permits the crank 37 to be 5 rotatable continuously in the same direction, while being always in position to be operative for opening or closing the lock.

My invention is thus seen to comprise a bolt movable outwardly and laterally of a lock to engage a keeper or jamb piece in jimmy-proof position, and novel bearing means co-operating with the bolt member for effecting the desired motion of said member. Said bearing means is seen to comprise a member having substantially fixed tilting relation therewith along a line parallel to the line of outward throw of the bolt, and other means spaced therefrom and having combined sliding and bearing relation to the bolt member and arranged to exercise an abutment pressure against the member aforesaid to render the bolt jimmy-proof. Restated in other words, the invention can be regarded as comprising a bolt tiltable laterally of the lock, spaced pivot means being provided at the sides of the bolt for tilting the same and by abutment thereon to prevent undesired movement of the bolt back into normal position. The invention takes more specifically, the form of a two-part expansible bolt engaging in a novel manner with a single bearing member and having cam means co-operating with suitable guide or pivot means to expand the bolt by causing the same to move about the bearing at 21. The principle both of the motion and of the construction are of an exceedingly simple nature requiring a minimum of parts and thus insuring strength and reliability.

It is to be noted that the members 13, constituting together a bolt structure, partake of three distinct types of movement: First, from the position of Fig. 1 the ends that are together along the line 17 remain together until the faces 18 strike the turning points 15. In other words, the bolt members move in a right line or in the same direction bodily as a unit. From this fact it follows that the leading ends of the bolt members will enter the opening in the keeper or jamb piece between the lips 36 even though there may exist a material degree of space between the door members and the jamb member, or even though the keeper may be somewhat higher or lower than was intended under perfect conditions of attachment. The second movement is a combined oscillation or locking movement and forward projection. This movement, however, is completed by the time the projections or lugs 35 reach the abutments 14, bringing the bolt members into the third stage or species of movement, namely, a bodily or unitary movement with the inner ends thereof in

contact along the line 16 as shown in Fig. 2. This third movement, consequently, is in a right line only, being so compelled by the gliding of the lugs 35 toward the lips 15 and between the abutments 14. The lips 15 constitute fixed pivots around which the bolts tilt substantially coincident with the passage of the bearing trunnions 21 through the transverse plane of the lips 15, i. e., transverse to the path or direction of sliding 75 movement of the bolts.

I claim:

1. In a lock, the combination with a casing and a bolt movable outward of the casing along a certain path, of actuating means for the bolt comprising a pivot member movable outward in unison with the bolt and an abutment on the casing serving to cause the bolt to tilt laterally of said path while continuing its movement outward, said abutment coacting with the bolt to prevent the same from tilting back to original position until after the bolt and pivot member are partially retracted.

2. In a lock, the combination of a casing, a bolt movable outward therefrom and tiltable laterally thereof for rendering the lock jimmy-proof, said casing having a fixed pivot and the bolt having a concavity on one side substantially midway between its ends into which the pivot projects, and means for throwing the bolt outward from the casing into operative position comprising an actuator having fixed bearing engagement with said bolt at a point upon the side thereof opposite said concavity and serving to cause the tilting of the bolt around said casing pivot.

3. In a lock, the combination of a casing, a bolt movable outward therefrom and tiltable laterally thereof, means having fixed bearing engagement with the bolt for moving the same outward as aforesaid, and fixed abutment means secured to the casing and adapted to engage the bolt to cause complete lateral tilting thereof before the first-mentioned means has reached its outward limit of movement, the casing abutment means having abutment relation with the bolt in a direction perpendicular to the path of outward projection of the bolt while the first-mentioned means has abutment with the bolt in a direction parallel to said path.

4. In a lock, the combination of an expansible bolt comprising a pair of co-operating locking members, actuator means comprising a member having substantially unitary bearing relation with both bolt members, fixed abutment means, said actuator and abutment means being operative for expanding the bolt and co-operating with each other to retain said bolt in operative expanded position.

5. In a lock, the combination of an expansible bolt comprising a pair of co-operating

- locking members, actuator means comprising a member having substantially unitary bearing relation with both bolt members, fixed abutment means, said actuator and 65
 5 abutment means being operative for expanding the bolt and co-operating with each other to retain said bolt in operative expanded position, the abutment means serving as pivotal means spaced from the bearing members 70
 10 and adapted to cause the bolt members to tilt from each other for expansion.
6. In a lock, the combination of an expandable bolt comprising a pair of co-operating locking members, actuator means comprising 75
 15 a member having substantially unitary bearing relation with both bolt members, fixed abutment means, said actuator and abutment means being operative for expanding the bolt and co-operating with each other to retain 80
 20 said bolt in operative expanded position, said abutment means comprising a pivotal means spaced upon opposite sides of said bolt members and having abutment relation with the individual bolt members
 25 when expanding as aforesaid; said bolt members having abutment with each other along the line joining said actuator bearing means.
7. In a lock, the combination of an expandable bolt comprising a pair of co-operating locking members, actuator means comprising a member having substantially unitary bearing relation with both bolt members, fixed abutment means, said actuator and abutment means being operative for 85
 30 expanding the bolt and co-operating with each other to retain said bolt in operative expanded position, said bolt members having open bearings for receiving the actuator bearing member.
- 40 8. In a lock, the combination of an expandable bolt comprising a pair of co-operating locking members, actuator means comprising a member having substantially unitary bearing relation with both bolt members, fixed
 45 abutment means, said actuator and abutment means being operative for expanding the bolt and co-operating with each other to retain said bolt in operative expanded position, said bolt members having guideways 90
 50 lying adjacent to each other, and the actuator having portions entering said guideways.
9. A door lock comprising a bolt consisting of two parts, the two parts of the bolt having abutment relation with each other first at one end and later at the other end and being 95
 55 slidable as a unit and tiltable with respect to each other while sliding.
10. A door lock comprising a bolt consisting of two parts, the parts of the bolt being disposed in close operative relation to each 100
 60
- other at one end and adapted to slide as a unit, the other end portion of the bolt parts being spaced from each other, and means to slide the bolt and at the same time cause said spaced end portions to approach each other while the opposite end portions thereof diverge from each other.
11. A lock, including a bolt, comprising a pair of bell-crank levers arranged with the inner edges of their outer arms adjacent each other, a pivot pin common to said levers and acting as a fulcrum therefor, means for projecting said pin, and means engaging said levers to rock the same at a stage in such projection to cause the outer arms thereof to diverge.
12. A lock, including a bolt, comprising a pair of bell-crank levers arranged with the inner edges of their outer arms adjacent each other, a pivot pin common to said levers and acting as a fulcrum therefor, means for projecting said pin, the inner arms of said levers being formed with recesses in their inner edges for the accommodation of such means, and means cooperating with said levers and acting at a certain stage during the projecting thereof to rock the same to cause the outer arms thereof to diverge.
13. A lock, including a bolt, comprising a pair of bell-crank levers each having arms of substantially equal length, the inner edges of the outer arms being disposed adjacent each other when said bolt is retracted, means acting as a fulcrum for said levers, means for projecting said fulcrum, and means cooperating with said levers and acting during a stage in the projection thereof to cause the outer arms to diverge and bring the inner edges of the inner arms of said levers to planes adjacent each other.
14. A lock, including a bolt, comprising a pair of bell-crank levers arranged with the inner edges of their outer arms adjacent each other, a pivot pin common to said levers and acting as a fulcrum therefor, a lock case, means forming a part thereof and bearing against said levers to rock the same around said fulcrum as said bolt is moved outwardly, and means for projecting said pin to a point beyond said last named means.
15. A lock, including a pair of angular levers, alternately having the inner edges of their different arms adjacent each other, said levers providing a bolt, means providing a fulcrum for said levers, and means for shifting said fulcrum in opposite directions to alternately cause the arms of the two levers to diverge.

In testimony whereof I affix my signature.

FRANCIS J. DOWLING.
